[57] CLAIM

The ornamental design for a combined cassette holder and divider for a cassette storage tray, as shown and described.

DESCRIPTION

FIG. 1 is a front-elevational view of the combined cassette holder and divider for a cassette storage tray showing our new design;

FIG. 2 is a side elevational view, the opposite side being a mirror image thereof;

FIG. 3 is a top plan view;

FIG. 4 is a rear elevational view;

FIG. 5 is a bottom plan view; and

FIG. 6 is a front perspective view thereof.

FIG. 1

FIG. 2

FIG. 3

FIG. 4

FIG. 5

FIG. 6
